RECEPTACLE BACK COMB CONSTRUCTION

Charles Castelli, Union City, N. J., assignor, by
mesne assignments, to Columbia Protekosit Company, Inc., Carlstadt, N. J., a corporation
of Delaware

Application October 29, 1949, Serial No. 124,309

3 Claims. (Cl. 132—79)

1

This invention relates to purse or pocket size combs and more particularly is directed to a comb construction having an improved built-in receptacle-compartment formed in the back for releasably retaining bobby pins, hair pins, cosmetics or the like personal articles.

Among the object of the invention is to generally improve devices of the character described, which shall comprise few and simple parts that are readily assembled to form a rugged yet neat appearing purse or pocket comb having a hollowed back portion forming a receptacle-compartment with a swingable cover closure therefor, which shall be of light-weight construction but adapted to withstand rough usage, which shall be relatively cheap to manufacture in quantity production, as by molding of plastic resinous material, and which shall be practical and efficient to a high degree in use.

Other objects of this invention will in part be obvious and in part hereinafter pointed out.

The invention accordingly consists of the features of construction, combination of elements, and arrangement of parts which will be exemplified in the construction hereinafter disclosed, the scope of application of which will be indicated in the claims following.

In the accompanying drawing in which one possible illustrative embodiment of the invention is shown,

Figs. 1, 2 and 3 are front elevational, end and top plan views of a purse or pocket comb constructed to embody the invention showing the cover of the receptacle-compartment in closed position.

Figs. 4 and 5 are enlarged cross sectional views taken on lines 4—4 and 5—5, respectively, of Fig. 1, showing details of the receptacle-compartment construction formed in the comb back, and

Fig. 6 is a sectional view similar to Fig. 5 showing the cover closure swung to a full open position.

Referring in detail to the drawing, 10 denotes a purse or pocket comb constructed with a built-in receptacle-compartment 10a in the back thereof embodying the invention. Comb 10 preferably may be made of molded plastic resinous material, colored, opaque or transparent as desired, and is adapted to provide a bobby pin or cosmetic receptacle, the overall structure being made of a size to readily fit into a purse, handbag or pocket.

As seen in Figs. 1, 2, 3 and 5, purse comb 10 may have a back 11 mounting along edge border 11a thereof, a row of comb teeth 12 and,

if desired, be provided with heavier terminal teeth 12a at opposite ends thereof.

Comb back 11 may be formed with a pair of spaced apart end portions 11b extending from said edge border 11a in a direction opposite to teeth 12 and lying substantially in the same plane thereof.

End portions 11b each may have either a plain surface (not shown) or carry decoration or trimming in any desired manner, as for example, flutes D extending between spaced apart parallelly aligned projecting ribs 11c which with said flutes serve as finger gripping means as shown in Figs. 1 and 2.

Comb 10 provides the improved built-in receptacle 10a in a midportion of comb back 11 between end portions 11b in the form of a compartment which may be cylindrical-shaped, of any desired cross-sectional configuration. As shown in Figs. 4, 5 and 6 receptacle-compartment 10a is circular in cross-section and includes longitudinally split tubular wall 13, substantially one half 13a serving as a relatively stationary cylindrical wall compartment portion integrally formed with edge border 11a and also with peripheral edges of a pair of spaced circular end walls 13b which lie in planes substantially normal to said plane of comb back 11.

A swingable mating cover 13c is provided similar in cross-sectional shape to receptacle wall 13a complementing the latter to form, when in closed position, the remaining half closure for receptacle 10a.

Cover 13c may be pivoted in position by any suitable means, as for example, integrally formed pintles 13d aligned along longitudinal edge 13e and extending in opposite directions to engage bearing bores 13f provided in end wall 13b as is clear from Figs. 4, 5 and 6. To retain cover 13c in closed position suitable snap locking means may be provided and as shown in Fig. 5 may include a longitudinal extension lip 13g projecting from the free edge of cover 13c to overlie free edge 13h of wall 13a with ridge 13j engaging groove 13k formed on the underside of lip 13g.

Each of the end portions 11b may be provided with a free edge border 11d in alignment with lip 13g and of substantially the same thickness to give comb 10 a finished appearance.

When the comb 10 is made by injection molding methods, spaced apart communicating transverse passageways 11f are provided in edge border 11a adjacent end walls 13b, said passageways 11f extending from the exterior side of the comb 10 opposite said cover to terminate just

beyond edge border bevel 11e, inner portions of said passageways 11f being constructed and arranged to form said bearing bores 13f, as is clear from Figs. 4 and 5.

After constructing the parts of the comb 10 as described above, the cover 13c may be hinged thereto in assembly by inserting one of the pintles 13d into its corresponding bearing bore 13f and then by flexing, that is, bowing the cover 13c along edge 13e the other pindle 13d may 10 readily be inserted in its bearing bore 13f.

The utility of the comb 10 with receptacle-compartment 10a will now be apparent. After comb 10 is assembled in the manner above described, the cover 13c may be swung from a full open position shown in Fig. 6, the bevel 11e acting as a clearance and limiting stop therefor, to a closed position in which lip 13g overlies free edge 13h of wall 13a. Ridge 13j then engages in groove 13k for resilient snap locking. As seen in Fig. 1 the planes of end walls 13b may be formed to converge upwardly so as to provide an abutment closure formed in cooperation with similarly converging side edges 13m when said resilient snap locking means is in said closed position.

It will thus be seen that there is provided an improved comb construction having a built-in receptacle compartment whereby the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A comb construction having a receptacle-compartment of the character described comprising a one-piece molded body having an elongated comb back and a row of comb teeth extending from an edge border of said back lying in a common plane, a pair of spaced apart end walls for said compartment formed in a midportion of said back disposed in angular relation to said common plane, a split tubular wall portion 50 extending between said end walls from a peripheral edge thereof forming approximately a half

of a tubular side wall of the compartment, a mating cover extending between said end walls forming the other half of said compartment side walls, hinge means for swingably mounting said cover on said end walls including a pair of pintles extending from opposite edges thereof, said end walls having bearing bores for receiving said pintles, said cover being of resilient construction for flexing between said pintles to form a snap-in engagement of said pintles with said bearing bores, and a transverse passageway extending through said edge border from the exterior side of the comb opposite said cover terminating in each of said bearing bores.

2. The comb construction as defined in claim 1 in which said edge border has a bevel extending between said end walls as a clearance and limiting stop for said cover.

3. A comb construction having a receptacle-compartment of the character described comprising a one-piece molded body having an elongated comb back and a row of comb teeth extending from an edge border of said back lying in a common plane, a pair of spaced apart end walls for said compartment formed in a midportion of said back disposed in angular relation to said common plane, a split tubular wall portion extending between said end walls from a peripheral edge thereof forming approximately a half of a tubular side wall of the compartment, a mating cover extending between said end walls forming the other half of said compartment side wall, hinge means swingably mounting said cover on said end walls, said hinge means including a pair of pintles extending from opposite edges of said cover, said end walls having bearing bores for receiving said pintles, and said cover being of resilient construction for flexing between said pintles to form a snap-in engagement of said pintles with said bearing bores.

CHARLES CASTELLI.
